UNITED STATES PATENT OFFICE.

ALFRED L. ROWE, OF CHICAGO, ILLINOIS.

DESIGN FOR SHEET-GLASS.

SPECIFICATION forming part of Design No. 22,097, dated January 3, 1893.

Application filed November 14, 1892. Serial No. 452,008. Term of patent 7 years.

To all whom it may concern:

Be it known that I, ALFRED L. ROWE, a citizen of the United States, residing at Chicago, in the county of Cook and State of Illinois, have invented or discovered a new and useful Design for Sheet-Glass, of which the following is a specification.

In the accompanying drawings which make part of this specification, Figure 1, is a plan of a piece of sheet glass ornamented with my design. Fig. 2 is a broken cross section through the same.

My design consists in a sheet of glass having upon its surface a pattern comprising a

series of open eyed daisies thickly strewn 15 thereon.

I use daisies of conventional design, as seen at *b*, *b*, and *c*, *c*, and cover the glass closely with them.

I claim,

The design for sheet glass as herein shown and described.

In testimony whereof I have hereunto set my hand this 31st day of October, A. D. 1892.

ALFRED L. ROWE.
